AUTOMATIC REWINDING DEVICES FOR WEBS
OF PAPER AND THE LIKE

Louis Jean Champon, Paris, France, assignor to Societe
d'Etudes de Machines Speciales, Paris, France
Filed June 20, 1960, Ser. No. 37,506
Claims priority, application France June 29, 1959
11 Claims. (Cl. 242—56)

The present invention relates to a rewinding machine for webs or bands of paper, cardboard, cellulose film or other similar materials such as are used on reel-fed machines, for example rotary printing machines.

Generally, it is necessary to stop a rewinding machine when a reel is filled and replaced by an empty rewind mandrel to which the end of the web is stuck. These operations waste time and a good deal of paper or the like.

An object of the invention is the provision of a device which will enable the web to be cut and to be automatically transferred to a new mandrel when the current reel has received a predetermined length of rewound web.

By such a machine the rewinding operation is effected automatically without its being necessary to stop the machine. It is sufficient simply to replace the finished reels, as they are completed, by empty mandrels.

Other objects and a fuller understanding of the invention may be had by referring to the following description and claims, taken in conjunction with the accompanying drawings in which:

FIGURE 1 is a view, in longitudinal vertical section, of one form of an automatic rewinding device according to the invention.

FIGURE 2 is a diagram of the device for eliminating the pressure from the suction drum.

FIGURE 3 is a diagram of the electrical circuits which control this device; and

FIGURE 4 is a longitudinal vertical section of another preferred form of automatic rewinding device.

As shown in FIG. 1, the automatic rewinding device according to the invention comprises a pair of traction rollers 4 and 5 drawing the web 3 to the rotary cutting device designated in its entirety by the number 6. This web 3 is delivered through a pair of feed rollers 1 and 2 which may, for example, form part of a printing machine.

The rotary cutting device 6 comprises, as is usual, a rotary cylinder 7 carrying a knife 8 and a counterknife 9 carried by a lever 11. The lever 11 is journaled upon a spindle 12 and carries at one of its ends a roller 13 which is pressed against a cam 14 by a spring 15.

The lever 11 has a tooth 11a which may be engaged by means of a detent which is biassed by a spring 17. The detent 16 is actuated by an electromagnet 18.

In the drawing, the counter-knife 9 is shown in the effective cutting position and comes into contact with the knife 8. In this position the detent 16 is disengaged from the tooth 11a. The cam 14 makes one complete turn per cycle of the machine, this cycle being determined by the rotation of one turn of a rotary endless suction conveyor. This device comprises a suction drum 19 with which the web 3 comes into contact after passing the rotary cutting device 6 and a pair of rollers 21 and 22.

During the rewinding operation, the counterknife 9 of the rotary cutting device is normally deflected downwards so that the knife 8 does not come into contact with it. In this position the tooth 11a of the lever 11 is engaged with the detent 16.

The suction drum 19 is pierced with holes 19a over one segment of its periphery. The interior of this drum is connected by means of a channel 23 (FIG. 2), in which an electrically operated valve 24 is interposed, with a vacuum chamber 25 in which a vacuum is maintained by means

2

of a pump 26. During the rewinding operation, the electrically operated valve 24 is closed so that there is only atmospheric pressure inside the drum 19.

The rotary cutting device is connected effectively with the suction drum 19 in such a way that the cylinder 7 effects a number of complete turns that is an integral multiple of the number of revolutions of the suction drum 19 (e.g. three turns of the cylinder 7 to one turn of the drum 19).

10 The suction drum 19 is rotated in such a way that its circumferential speed is very slightly more than the circumferential speed of the feed rollers 1 and 2, so that the web 3 is slightly stretched. The web 3 passes between the drum 19 and an apron or belt 27, one end of which 15 passes round a fixed roller 28 and the other end round a movable roller 29 mounted at one end of a lever 31. The position of this lever 31 and, in consequence, the tension of the belt, may be regulated by means of a screw 32.

The upper part of the framework of the device comprises two inclined guide channels 33 and 34, in which 20 travel the mandrels 35 and 36 on which the reels are wound.

In FIG. 1 the reel 37 in course of operation presses by its own weight on the drum 19 and is thus rotated about 25 the axis of the mandrel 36. The reel, as shown, is practically at its maximum diameter at the end of the winding. On the other hand, an empty mandrel 35, on which the next following reel is to be wound, is mounted in the guide channel 33.

30 Means are provided for keeping the empty mandrel 35 away from the suction drum 19 during the winding of the reel 37. For this purpose, for example, rocking hubs 38 and 39, respectively having recesses 38a and 39a in their peripheries, may be positioned so as to act as supports for mandrels 35 and 36 respectively. The rocking hub 39 is shown in the normal position in which the corresponding mandrel is kept away from the drum 19. The rocking hubs 38 and 39 are respectively biassed towards their normal positions by springs 41 and 42 and are actuated by electromagnets 43 and 44, respectively, to present their recesses 38a and 39a to the mandrels 35 and 36. In FIG. 1, an electromagnet 43 is assumed to be excited so that the recess 38a of the rocking hub 38 is facing a disc 35a which is integral with the empty mandrel 35. Consequently, the latter can fall to the lowest point of the guide channel 33 and thus come into contact with the suction drum 19.

The means for automatically discontinuing rewinding on the mandrel that is full, or substantially so, comprise, 50 in the example under consideration, electric switches 45 and 46 arranged and so disposed relatively to the guide channels 33 and 34 that these switches are actuated when the reels formed on the mandrels 35 and 36 have reached predetermined diameters.

55 The operation of the rewinding device shown in FIGS. 1 and 2 will now be described in detail with reference to FIG. 3 of the drawings.

In FIG. 3 are shown the electromagnet 18 which controls the rotary cutter 6, the electrically operated valve 24 and the electromagnets 43 and 44 that actuate the hubs 38 and 39 for maintaining the mandrels 35 and 36 out of contact with the suction drum 19. Furthermore, the switches 45 and 46 are two-way switches, each comprising two movable contacts 45a, 45b and 46a, 46b as shown in FIG. 3.

60 The suction drum 19 causes to rotate, at the same speed, three cams 47, 48 and 49 which actuate contacts 51, 52 and 53 respectively. At certain points on the cycle (i.e. at certain predetermined angular positions of the suction drum 19), these contacts are closed or transferred. The angles of the contacts 51, 52 and 53 thus correspond to the moments when these contacts are actu-

ated by their respective cams. These contacts furthermore control the excitation of several relays 54, 55, 56, 57, 58, 59 and 60 which are normally de-energized.

Let it be supposed that the reel 37 which is being wound has reached the maximum diameter envisaged. As a result the mandrel 36 actuates the switch 46 which consequently closes the contacts 46a and 46b which are normally open. The closure of contacts 46a prepares a circuit for relay 55 and the closure of contacts 46b prepares a circuit for relay 54.

At a specific point in the rotation cycle of the suction drum 19 (this point being situated after the suction holes 19a pass under the reel 37 and before the rotary cutter starts to function) the cam 47 closes the contacts 51. This energizes the relay 55, since the contact 46a has been closed and the contact 54b is normally closed. The consequent closing of the contact 55b brings about the energization of the electromagnet 18 controlling the rotary cutting device. This latter thus causes the detent 16 (FIG. 1) to pivot, and as the cam 14 is arranged in such a way that the roller 13 is on the part 14a of the cam which is closest to its centre, the counter-knife 9 comes into contact with the knife 8 and the web of paper 3 is then cut.

The beginning of the suction holes 19a on the drum 19 is arranged in such a way that, when the web 3 is thus cut, the new end of the web comes into contact with the drum 19 slightly before the first suction hole. The rollers 4 and 5 revolving continuously at a higher circumferential speed than cylinders 1 and 2 feed the end of the severed web to cylinders 21, 22 revolving at a circumferential speed equal to or higher than that of cylinders 4 and 5.

Cylinders 4 and 5 feed in turn the end of web 3 to cylinder 19.

At the same time as the rotary cutter is disengaged, a partial vacuum is created in the drum 19. It may be seen from FIG. 3 that the closing of the contact 55c causes the excitation of the relay 56, since the contact 52 is then in the normal, unactuated, position shown. The relay 56 is kept energized by its contact 56a which completes a locking circuit. The closing of the contact 56b energizes the electrically operated valve 24. Consequently, this latter opens at the same time as the electromagnet 18 is energized, so that a partial vacuum is caused inside the drum 19. Thus, when the new end of the severed web 3 comes into contact with the drum 19 it is held against the latter. The feeding of the new end of the web 3 is facilitated by the belt 27 which, at this spot, is pressed against the periphery of the drum 19.

Thus the drum 19 draws the new end of the web 3 until it is just under the empty mandrel 35, which is in the guide channel 33 and which has previously had glue applied. However, until this moment the mandrel 35 is kept away from the drum by the hub 38.

When the suction holes 19a of the drum 19 come under the mandrel 35, the cam 48 puts the contact 52 into the working position, so that the relay 57 is excited through the normally open contact 54c which is now closed, since the relay 54 is still kept excited by its contact 54a and the contact 46b. Thus, at this moment, the electromagnet 43 is energized through the closing of the contact 57a which is normally open.

The hub 38 rotates so that the recess 38a allows the empty reel 35 to drop down to the bottom of the guide channel 33 and the mandrel 35 comes into contact with the web 3 on the drum 19.

Simultaneously, as cam 48 transfers contact 52 into its working position, the relay 56 is deenergized so that the contact 56b opens and the current to the electrically-operated valve 24 is cut off. Consequently, the drum 19 is no longer under partial vacuum.

The end of the web then leaves the drum, since it is stuck to the mandrel 35, and the web 3 winds itself round this mandrel.

The new reel begins to form on the mandrel 35, whilst

the operator will have all the time necessary to remove the old reel 37 and replace it by a new empty mandrel 36. The removal of the reel 37 causes the opening of the contacts 46a, 46b of the switch 46 and the de-energization of the relay 54, which re-establishes normal working conditions.

When the reel wound upon the mandrel 36 has reached its maximum diameter, the switch 45 closes, causing the excitation of the relay 54, as previously.

10 The above operations are then repeated, that is to say the closing of the contact 51 by the cam 47 energizes the relay 58, thus energizing the electromagnet 18 controlling the rotary cutting device by the closing of the contact 58b and the setting up of a partial vacuum in the suction drum 19 through the energization of the electrically operated valve 24 by the closed contact 59b. On the other hand, it is the cam 49 instead of the cam 48 which is active in this case, transferring the contact 53, when the holes 19a come under the mandrel 36. The transfer 15 of this contact causes de-energization of the relay 59 and thus de-energization of the electrically-operated valve 24, so that there is no longer a partial vacuum in the drum 19.

Simultaneously, the relay 60 is excited and the closing 25 of its contact 60a causes the feeding of current to the electromagnet 44, so that the mandrel 36, to which glue has previously been applied, comes into contact with the drum 19. The web 3 then winds round this mandrel.

Referring now to the form of the invention illustrated 30 in FIG. 4, the webs to be rewound, 73 and 74, are cut lengthwise from a very wide web 70, by means of a rotary cutting device comprising the cylinders 71 and 72. The web 73 moves upwards after leaving this rotary cutting device and the web 74 moves downwards.

35 It is obvious that the web 70 could be cut simultaneously into several separate webs like 73 and 74, each of these being rewound on an independent unit.

The rewinding devices for the webs 73 and 74 being identical, only the device for rewinding the web 74, moving downwards, is described.

The web 74 can either be rewound on the mandrel 75 which moves in the groove 76, or on the mandrel 77 which moves in the groove 78.

With the mandrels 75 and 77 are associated the suction drums 79 and 80 respectively. These drums move in rotation round their shafts 81 and 82 respectively, and are tangential to cylinders 83 and 84. Their peripheries have respectively perforated sections 79a and 80a occupying corresponding angular subtents. Inside these drums there are fixed cylindrical sections 79b and 80b which seal the perforated sections 79a and 80a as they pass thereover.

Above the first suction drum 79 is arranged a rotary cutting device comprising a rotary cylinder 85 carrying a knife 86 and a counter-knife 87 carried by a lever 88. The lever 88 is journalled upon a spindle 89 and has at one end a roller 90 which is pressed against a cam 91 by a spring 92.

60 The lever 88 has a tooth 88a which can be engaged by means of a detent 93 which is biassed by a spring 94. The detent 93 is actuated by an electromagnet 95.

The device for feeding the web 74 comprises a track 96, over which the web glides, with the help of several pairs of feed rollers like the rollers 97 and 98.

65 With the suction drums 79 and 80 are associated gluing discs or drums 99 and 100 respectively, which turn continuously in trays 101 and 102 which are filled with glue. The discs 99 and 100 are mounted at one end of levers 103 and 104 respectively, pivoting round shafts 105 and 106. The other ends of the levers 103 and 104 are actuated by electromagnets 107 and 108 respectively and these levers are restored to their normal positions by springs 109 and 110, which thus normally keep the gluing discs 99 and 100 away from the drums 79 and 80.

75 In FIG. 4, the different elements are shown in the

position which they occupy at the moment when the reel 111 formed by the web 74 on the mandrel 75 is finished.

At this moment, an electrical switch 112, actuated by the mandrel or the reel, energizes the electromagnet 95, at a given moment of the cycle, determined by a contact closed by a cam turning in synchronization with the drums 79 and 80 in a way similar to that described in reference to FIG. 3. Consequently, the counter-knife 87 is brought into proximity to the knife 86 of the cutting device.

Simultaneously, the electromagnet 107 is excited by the same contact that disengages the mechanism of the rotary cutter. The gluing disc 99 which turns constantly in the tray 101 containing the glue and which is normally kept away from the suction drum 79, comes into contact with the web 74.

At this moment, the web is glued and as it rotates the last turn is glued to the penultimate turn and the reel 111 is completely finished and glued without manual intervention by the machine operator.

In the meantime, the electricity supply to the electromagnet 107 has been cut off by a contact actuated by a cam and the disc 99 has been moved away from the suction drum 79, before the new end of the web passes in front of the disc.

The new end of the cut web 74 which is now in front of the rotary cutting device continues on its way instead of winding itself round the drum 79 and comes into contact with the suction drum 80, which has previously been set so that the suction holes 80a are in a correct position in relation to the new end of the web 74.

In the suction drum, the fixed cylindrical sections 79b and 80b serve to uncover progressively the suction holes 79a and 80a, so as to avoid any loss of suction when the web is drawn along by the drum.

The web thus winds itself round the suction drum 80 and, at the moment when it comes in front of the gluing disc 100, and this disc 100, actuated by the electromagnet 108, comes into contact with the web 74, applies glue along a certain length, then moves away, through a cam-controlled contact having cut off the supply of current to the electromagnet 108.

The glued web then comes into contact with the rewind mandrel 77 at the precise moment when the suction in the drum 80 is cut off. The web winds itself round this mandrel, without its having been necessary previously to apply glue to the mandrel, as described with reference to FIGS. 1, 2 and 3. This also obviates the necessity of having to keep the mandrel at a certain distance from the suction drum 80, as long as the web has not previously been rewound.

In the aforementioned devices, which have been described only by way of example, the initiation of a cycle comprising the severance of the web, the subjection of the suction drum to suction and the cutting off of the suction is effected by switches such as 45, 46 (FIG. 1), 112 (FIG. 4), these switches being actuated when a reel of web on a mandrel reaches a predetermined diameter.

According to another embodiment of the invention the initiation of said cycle could be controlled by other factors and more particularly as soon as the reel contains a predetermined number of tickets. In this event, it is only necessary to provide a totalizer for registering the number of tickets rewound on the reel and for initiating the cycle as soon as this number reaches a predetermined value. In this respect the totalizer controls, for example, a switch which is actuated when the predetermined number is reached, said switch having the same effect as the switches 45, 46, 112.

Although I have described my invention with a certain degree of particularity, it is understood that the present disclosure has been made only by way of example and that numerous changes in the details of construction and the combination and arrangement of parts may be re-

sorted to without departing from the spirit and scope of the invention as hereinafter claimed.

What I claim is:

1. A rewinding device for receiving a web of paper or the like and rewinding it upon separate mandrels in successive reels comprising a framework, a severing device for severing the web, at least one endless suction conveyor adapted to receive the web after it leaves the severing device and perforated over a part only of the periphery, means responsive also to a predetermined diameter of rewound web on one such mandrel for initiating effective severing action of the severing device, means for transferring the new end of the web, formed by severing, from the severing device to the suction conveyor, at least two guide channels provided in said framework and in which said mandrels are caused to travel so that these mandrels may engage the periphery of said suction conveyor, whereby the web is severed at the end of the rewinding operation, the new end of the web formed by the severance is presented to the perforated part of the conveyor periphery so as to be drawn by the suction thereagainst and to be conveyed thereby to the periphery of a mandrel bearing on the surface of the conveyor.
2. A rewinding device according to claim 1 comprising means normally precluding an empty mandrel, located in a guide channel, from contacting the conveyor, an electromagnet actuating said last named means in order to permit such contact after the effective severing action of the severing device, an electric switch controlling said electromagnet and means for actuating said switch, said last named means being moved synchronously with the conveyor.
3. A rewinding device according to claim 2 wherein said means normally precluding an empty mandrel from contacting the conveyor comprises a rocking hub having a slotted periphery cooperating with the axis of the mandrel, said hub being actuated through said electromagnet.
4. A rewinding device according to claim 1 comprising means for applying suction to the endless conveyor when the new end of the web meets the conveyor and for cutting off this suction when the new end of the web on the conveyor meets the periphery of a mandrel, so that the new end may adhere to the mandrel and be stripped from the conveyor.
5. A rewinding device according to claim 1 wherein the severing device comprises a rotary device having a blade arranged to rotate through an integral number of revolutions in every complete cycle of the endless conveyor, a movable counter-blade wherewith said blade co-operates for effective severing action, and means for moving the counter-blade from a remote position to a position in which it cooperates with the blade for effective severing action.
6. A rewinding device according to claim 1, comprising a suction system, an electromagnetically operated valve interposed between said suction system and the suction conveyor, an electric switch controlling said valve, and means for actuating said switch to On and Off positions, said last means being moved synchronously with the suction conveyor.
7. A rewinding device according to claim 1 comprising a continuous travelling flexible belt stretched over part of the conveyor surface so as to guide the new web end on to and to urge it against the conveyor surface.
8. A rewinding device according to claim 1, wherein a separate endless suction conveyor is provided for each mandrel.
9. A rewinding device according to claim 8 comprising a gluing device associated with each conveyor, means for moving said gluing device into effective contact with the web on the conveyor to apply glue thereto after the severance of the web by the severing device, so that the last turn on the reel is glued to the penultimate turn; and means for leading the new end of the web formed by the

severance to another conveyor to be wound on an empty mandrel.

10. A rewinding device according to claim 9 comprising means for moving the gluing device associated with said other conveyor into effective contact with the new end of the severed web on that other conveyor so as to cause that new end to be stuck to the empty mandrel.

11. A rewinding device according to claim 8 wherein each conveyor is a rotary cylindrical drum and comprising a fixed shield occupying a segment of a circle disposed within and adjacent the wall of the drum to screen the

perforations thereof when they pass that segment, thereby minimizing leakage of suction where the drum is not covered by the web.
